FOOT-SUPPORTING MEANS

Hans Cäsar Knellwolf, Zurich, Switzerland

Application August 4, 1947, Serial No. 765,981
In Switzerland May 13, 1947

4 Claims. (Cl. 36—71)

1

The progressive deterioration of the condition of the human feet has led to the creation of innumerable defensive and correcting means. By supporting insets and so called health shoes it has been attempted to preserve the required faculty of walking and standing of the foot, or to restore it. The fact that the individual bones of the foot skeleton are held together by the strength of its muscles and ligaments and that accordingly a deformation of the foot can only be caused by the weakening of these ligament tissues has brought science to realize that an artificial support without simultaneous invigoration of the ligament tissues cannot be the right way. On the contrary, it has been proved that by the more or less rigid support of the foot arch the foot muscles in particular are hampered in their activity and are consequently gradually weakened. Therefore, the method applied over many years in the treatment of foot diseases was quite unsound in that it further damaged the weakened tissues of the foot by preventing the necessary work of the foot. This has led to making a foot-suffer more and more dependent on his foot supports and even incapable of walking at all without this aid after some time, the foot being gradually weakened by the prevented muscle activity and requiring a still higher and more rigid support.

Of course, a badly sunken foot cannot be healed simply by muscle gymnastics but has to be brought into its normal position by a support first. A therapeutical success will, however, be possible only if the supporting means does not hamper the activity of the muscles securing the foot arches but, on the contrary, strongly stimulates such activity.

The most important tensile tissues of the foot arch are the flexor muscles of the toes, particularly those of the big toe. Consequently, in the interest of an invigoration of the foot arch the free unhampered activity particularly of these muscles has to be preserved. The hitherto usual foot supports, while shoring-up the foot arch, have subjected the muscles of the foot sole at the same time to a strong pressure, and have thereby hampered their mobility to a great extent. The consequence has been a gradual muscle atrophy and therefore a forcible weakening of the foot.

With the object of removing the existing drawbacks the present invention provides a device in the form of a shoe inset, sole or the like which fulfills the double task of supporting the foot and at the same time invigorating the same.

2

The device comprises a resilient bridge in the range of the outer recess of the balls of the foot (transverse planar arch) which raises the foot there, prevents it from developing outwards when walking, and forces it to perform a natural developing movement of the foot over the big toe.

By way of example four embodiments of the invention are shown on the accompanying drawings.

Fig. 1 shows, as the first embodiment, a lady's shoe with the device built-in as a shoe inset, in lateral view and longitudinal section.

Fig. 2 is a plan view of the sole of the shoe.

Fig. 3 shows, as a second embodiment, the device built-in between the outer sole and the insole of a shoe, in elevation and in section.

Figs. 4 and 5 show, as a third embodiment, the device as an inset sole in longitudinal section and plan view, respectively.

20 According to the first embodiment shown in Figs. 1 and 2 the device is cemented on the insole 1 of the shoe 2, forming an inset. In a pad 3 a resilient steel plate 4 is inserted into a recess as a bridging means therefor, and is covered on its under side by a cover 5 of the same shape as the pad 3. The cover 5 is cemented with the pad 3 which may, for example, consist of rubber. Above the pad 3 and cemented to it there is a sticky tape 6, preferably of oilcloth or the like. 25 By means of this sticky tape 6, which projects beyond the pad on three sides, the components 3, 4 and 5 are stuck on the insole 1 of the shoe 2. The bridging piece, i. e. the resilient steel plate 4, runs approximately from the outer border portion 3 of the shoe, obliquely, from the small toe side of the front portion of the foot towards the big toe side of the medium portion of the foot (metatarsus), perpendicularly to the direction of rolling-off of the foot over the big toe. Between 30 the insole 1 and the cover 5 there is a cavity 7, which is bridged by the steel plate 4, below the latter, which permits resilient yielding of the bridging piece. The end of the resilient steel plate 4 pointing towards the outer border portion 3 lies substantially in the range of the front metatarsal joint of the small toe. By means of the inset as described a resilient bridging of the outer arch of the ball of the foot is formed which raises the foot there in a spring-fashion 35 and thereby prevents a rolling movement in the outward direction when walking, thus compelling the natural tread development of the foot over the big toe. Consequently the big toe is stimulated to increased muscular activity and thereby 40 the power of resistance of the foot is invigorated.

As shown in Fig. 3 a cushion 10, which is equipped with a steel plate 9, is embedded between the outer sole 11 and the insole 12 of the shoe 13.

The inset sole according to Figs. 4 and 5 consists of a sole proper 14 which may be covered by sheet material if desired. In the range of the outer ball of the foot a pad-like support 15 is cemented to the lower surface of this sole 14. The latter again comprises as a bridging piece an embedded resilient steel plate 16 which runs obliquely inwards and backwards as in the first embodiment. The sole 14 is covered on its under side by a soft sole 17 which makes the tread pleasant and serves as a protection against the device sliding within the shoe. In the heel portion of the sole 14 there is a cut-out 18 which has a cuneiform shape with the point directed towards the small toe. The edge portion thereof is sharpened so that a bed 19 for the human heel is formed true to shape which may be open, or, as shown, covered by the soft sole 17. In addition to the springing of the ball of the foot, a pleasant relief to the heel is afforded by means of the heel cushion of the device. By the pointed shape of the heel bed and/or by the cut-out 18 an oblique transversely directed rising slope for the slight lifting of the sunken heel bone is achieved. Due to the applied soft sole 17, the edge portions of the cut-out 18 cannot tilt up should they get brittle due to perspiration.

In all the embodiments the resilient bridging of the recess in the ball of the foot can of course be effected, instead of by a resilient steel plate, alternatively by means of covered short torsion springs arranged obliquely in line, or by a piece of more or less resilient filling material.

For the purpose of raising the resilient bridging the steel plate may be bowed or arched.

I claim:

1. In a shoe, in combination, a sole having outer and inner side edges, a substantially flat front portion, an inclined shank portion and a curved sole portion located between said front portion and said shank portion, merging into the same, and having a concave upper face, a resilient, flat, supporting strip located across said concave upper face of said curved sole portion and having opposite ends supported by said sole, one of said ends being located adjacent said outer side edge of said sole in the region where said curved sole portion merges into said flat front portion and the other of said ends being located substantially centrally between said side edges of said sole in the region where said curved sole portion merges into said inclined shank portion, so that said flat supporting strip extends diagonally over said curved sole portion and bridges the same; and a flexible cover sheet located over

said concave upper face of said curved sole portion and said resilient supporting strip, said flexible cover sheet extending over a greater area than said curved sole portion so as to rest against said front and shank portions of said sole.

2. A substantially flat, elongated shoe insert, comprising in combination, a flexible non-metallic top sheet having inner and outer side edges, a rear heel portion, a front end portion, and an intermediate shank portion; a resilient, flat, supporting strip located against the under face of said flexible top sheet and having one end thereof located adjacent said outer side edge of said top sheet and having the opposite end thereof located substantially centrally between said side edges of said top sheet, said one end of said strip being located nearer to the front end of said top sheet than said opposite end of said strip and said opposite end of said strip being located in the region where said front end portion of said top sheet merges into said shank portion; and a flat, flexible, non-metallic cover member located against the under face of said top sheet, covering said flat, supporting strip and being secured around the same to the under face of said top sheet.

3. A shoe insert as defined in claim 2, said shoe insert further comprising a flexible non-metallic bottom sheet of a softer material than said top sheet, of substantially the same configuration as said top sheet, being joined to the latter against the under face thereof and covering said flexible cover member.

4. A shoe insert as defined in claim 3, said top sheet being formed with an opening passing through said rear heel portion thereof and said bottom sheet being exposed through said opening so as to provide a recess to support the heel of the user of the insert.

40 HANS CÄSAR KNELLWOLF.
